COMBINED SHELF AND BRACKET

Filed May 17, 1920

INVENTOR.
A. F. Carlin.
BY S. P. Stanton.
ATTORNEY

UNITED STATES PATENT OFFICE.

ARVID F. CARLIN, OF NEW YORK, N. Y.

COMBINED SHELF AND BRACKET.

Application filed May 17, 1920. Serial No. 381,975.

To all whom it may concern:

Be it known that I, ARVID F. CARLIN, a citizen of the United States, and resident of New York, in the county of New York, 5 and State of New York, have invented certain new and useful Improvements in Combined Shelves and Brackets, of which the following is a specification.

The present invention relates to combined shelves and brackets; the object thereof being to provide a portable device of this character which comprises a shelf and supporting brackets therefor, said parts being attached in such novel correlation as to adjust 10 mit of their being folded and superposed over each other, whereby the device may be maintained in compact form for purposes of transportation and readily extended into shape for effective use on a wall or other 15 upright surface.

These and other objects are attained by employing a rectilinear or other shaped shelf-plate, brackets and brace-means in foldable relation therewith, and other novel 20 features all as hereinafter fully described and specifically set forth in the annexed claims.

In the accompanying drawings forming part of this specification, Figure 1 is a perspective view showing one example of my improved shelf and brackets. Fig. 2 is a 25 perspective view showing a slight modification. Fig. 3 is a vertical sectional view taken on the line 5—5 of Fig. 1. Fig. 4 is a vertical sectional view showing a slight 30 modification of shelf and bracket formation.

In the drawings, referring to Figures 1, 2 and 3,—1 indicates a rectilinear plate of sheet metal making a shelf and having a 35 beaded flange 2 extended around its four sides.

In hinged relation with said shelf, one at each end thereof, is a wire bracket 3. These brackets each embody an upright 4 40 and an obliquely extended part 5, the converging points of said parts being formed into an eye 6, for engaging a screw or other fastening means adapted to secure the bracket to a wall. The upper or free end of each 45 upright 4 is provided with an eye 7 adapted for receiving a screw, and a lateral extension or spur 8 which is in pivotal engagement with the rear side of the flange 2 of the shelf; the obliquely extended part 5 of each bracket is also provided with a 50 lateral extension or spur 9, for pivotal en-

gagement with the front side of the flange 2, said spur 9 having a bent head 10, formed after the bracket is placed, to securely retain the bracket in place.

The brackets 3 may further be provided with loops 11, which register on a horizontal plane when the device is placed on a wall and are adapted to engage a rod 12, for holding towels, etc.

In the construction shown by Fig. 2 of the drawings, I employ an upright bracket 3, of construction described above, and an obliquely extended bracket of similar construction, the eyes 6 of said brackets registering with each other for engaging a fastening screw. This arrangement of brackets may be employed for short shelves. For very long shelves I may employ two end brackets and an intermediate obliquely extended bracket to act as a brace for adding 55 stability to the device.

In Fig. 4 of the drawings I have shown a vertical sectional view showing a slightly modified form of shelf having a beaded front part 13 which interlocks with a part 14 of the oblique arm 5 of the bracket; and the upright 4 of said bracket is provided with a lateral and downwardly extended end part 15 which passes through the flanged 60 part 16 of said shelf.

When the device is not in use, or when it is desirable to transport or store it in a minimum of space the brackets are simply folded over on the bottom of the shelf, whereby they may be packed within a small 65 vertical space. When in use and fixed to a wall the brackets are simply unfolded and adjusted to a wall or other upright surface by means of screws or other suspending and fastening means.

Having thus described my invention, what I claim as new and desire to secure by Letters Patent, is:

1. A bracket shelf comprising a plate of sheet metal having the edge bent to form a bead on the upper portion with the margin projecting downwardly below the plate, a pair of brackets each composed of a rod looped at the middle portion to form an eye, 100 one upright arm projecting upwardly with the end portion bent to form an eye and the extremity bent laterally, the plate having apertures in the projecting flange to receive said bent ends, the other arm of each bracket being inclined and extending forwardly 105 at an angle to said upright arm with the end

portion bent to enter an apertured portion in the said bead, whereby said brackets can support the shelf at each end by fastening means passed through said brackets, and can also fold against the plate.

2. A bracket shelf comprising a plate of sheet metal having the edge bent to form a bead on the upper portion with the margin projecting downwardly below the plate, 10 a pair of brackets each composed of a rod looped at the middle portion to form an eye, one upright arm projecting upwardly with the end portion bent to form an eye and the extremity bent laterally, the plate having apertures in the projecting flange to

receive said bent ends, the other arm of each bracket being inclined and extending forwardly at an angle to said upright arm with the end portion bent to enter an apertured portion in the said bead, whereby said brackets can support the shelf at each end by fastening means passed through said brackets, and can also fold against the plate, one of said bracket members being longer than the other, whereby they can be brought together to form a corner shelf as set forth. 20 25

Signed at New York city in the county of New York and State of New York this 8 day of May, A. D. 1920.

ARVID F. CARLIN.
